UNITED STATES PATENT OFFICE.

WILLIAM W. DEAN, OF ELYRIA, OHIO; CURTIS B. CAMP, TRUSTEE, APPOINTED BY COURT.

ELECTRICAL SIGNALING.

1,125,490.

Specification of Letters Patent. Patented Jan. 19, 1915.

Application filed May 19, 1905. Serial No. 261,132.

To all whom it may concern:

Be it known that I, WILLIAM W. DEAN, a citizen of the United States, residing at Elyria, in the county of Lorain and State of Ohio, have invented certain new and useful Improvements in Electrical Signaling, of which the following is a specification, reference being had therein to the accompanying drawing.

10 My invention relates to electrical signaling, and particularly to what is known as harmonic or selective signaling for telephone systems. In such systems, where more than one station is served over a single line, modern standard practice calls for the employment of signaling means by which one station may be called up without alarming the other, or any of the others, if there be several.

20 In former systems devised by me I have employed a number of tuned vibrating reeds at the several stations, each reed responding to a certain frequency of alternating or intermittent current only. The reeds employed constituted the clapper rods of polarized ringers, and the clappers were adjusted to strike the gongs without the armatures touching the pole pieces. With such an arrangement, the initial rate or period of 25 vibration of each clapper rod is somewhat modified by contact with the gongs, and hence I found it necessary to resort to under-tuning or over-tuning the current or the mechanical parts, in order that the current 30 thrown upon the line to ring a particular station should correspond in periodicity to the modified or operative periodicity of the reed and clapper at the desired sub-station.

35 My present invention, while it includes the feature of a tuned reed at each station, is an improvement in every way over, and is to be distinguished from my former inventions by the following radically different principle and method of operation: In former cases I was forced to use gongs of different sizes, and it was necessary to have a very nice adjustment of relative frequencies, as well as a careful adjustment of the moving mechanical parts. In the present case, I 40 abandon all over-tuning and under-tuning entirely, and adjust my reed to respond to its own natural frequency, and this being determined, the current can be supplied at a corresponding frequency with absolute certainty.

45 In order to overcome the modifying effects of the gong strokes, I use three expe-

dients, first, I provide a very stiff spring mounting for the armature and clapper rod, second, I expose the armature to a cumulatively increasing force as it vibrates, and 50 third I expose the naked pole pieces to the ends of the armature, and so adjust the gongs that each end of the armature will strike its pole piece before the clapper touches the gong, the clapper then springing 55 over to strike the gong, and thus getting a very quick return. In practice the distance between the clapper and the gong may be say $\frac{1}{2}$ of an inch. With this construction and adjustment, I get a very sharp, clear 60 and powerful tone from the gongs, and perfect certainty of operation in selection.

65 It will be observed that my invention really covers a method as well as the apparatus for practising the method. In the 70 present case, I shall claim the apparatus only setting forth some specific features, such as a spring mounting of the armature and the means for tuning by sliding the clapper up and down the rod; but it is quite 75 obvious that my method is independent of these or any other specific limitations, being practicable with many different forms of apparatus and the same will be presented 80 and claimed in a separate application. 85

80 My invention will be fully understood upon reading the following detailed description, in connection with the accompanying drawings, forming a part hereof, in 90 which—

90 Figure 1 is a side view of a polarized signal bell or ringer embodying my invention; Fig. 2 is a section on the line $x-x$ of Fig. 1, looking to the right; and Fig. 3 is a perspective view of the clapper rod with its connected parts, removed.

95 Referring to the drawings, Q, is a pair of ringer magnets mounted upon the yoke B, which also carries the bent permanent magnet M, as shown. The cores q , q' of the electromagnets protrude at the lower ends and upon them, or upon the sleeve surrounding them is carried the armature yoke A. This is of non-magnetic material, extending from pole to pole and adjustably clamped thereto, 100 and having front and back downwardly turned extensions a , a' , slotted as shown at a^2 for the reception of the studs, d , d' on the armature support D. These studs are formed upon the terminal blocks, d^2 , d^3 connected by the stiff spring d^4 whose ends are 105 riveted or otherwise secured in slots in the 110

blocks. The studs are threaded and receive the nuts, d^5 , d^6 , which clamp the extensions of the yoke firmly upon the blocks, d^2 , d^3 , thereby securing the structure D in place.

5 The armature C is formed integral with the clapper rod C', out of punchings, in two halves, a "right" and a "left." Of course, in making the blanks these would all be the same, but in forming up the right would be turned one way and the left the other. Each left blank has a wing, c, a leaf, c', and a long stem, c².

10 Each right blank has a wing, c', a leaf, c² and a stem, c³. In assembling these parts, the spring d^4 is placed between the two leaves, c¹ and c⁵, which are riveted together through the spring. The stems, c² and c³ are then also riveted together, and the cylindrical clapper, c', is placed upon the rod thus produced. The ends of the spring, d^4 , being secured in the blocks, d^2 , d^3 , the structure of Fig. 3 is complete, and is ready for assembling in the complete ringer as shown in Figs. 1 and 2.

15 My selective reed is thus formed of the parts D and C', and its exact period is determined, or in other words it is tuned, by moving the clapper c' up or down until the exact pitch is reached which is desired. Of course, in making these bells in quantities it is possible to determine the exact point upon the clapper rod upon which the clapper of a given weight must be placed to give the desired result.

20 25 In operation, when current of any particular frequency is thrown upon the line, the reed or clapper rod of corresponding period will commence to buzz, and as it buzzes the armature wings, c, c', will approach to and recede from the pole pieces, q, q'. During each approach and recession the amplitude of vibration is increased, and the force exerted by the pole pieces is increased correspondingly. Action and reaction thus 30 35 succeeding and reinforcing each the other, the cumulative force soon causes one armature end to forcibly strike its pole piece, whereupon it will stop, but the clapper c' will continue its travel, the clapper rod C' 40 45 springing to permit this. The clapper strikes the gong, and instantly recoils. All this, on account of the magnitude of the cumulative force at the time of stroke, is accomplished substantially in the natural 50 55 period of the parts, hence the recoil from one side stroke assists in the opposite stroke, or to put it another way, energy is stored up in the yielding clapper C' to snap back and start the next stroke, the innate capabilities of all the parts being thus utilized, and 60 65 current, spring and stroke all acting well together.

In order that the adjustment of the gongs may be not only accurate but permanent, I mount each gong G or G' upon a post, g or

g', carried upon a pivoted adjuster, w² or w³, pivoted at its rear end, and threaded at its forward end to engage a worm, w, or w'. Each worm has a head W or W' and its shank is mounted to turn in drop bearings, 70 b, b', formed upon the yoke B. By means of a wrench the worms can be turned to adjust the gongs exactly, and when so adjusted no ordinary use or misuse will move them.

75 It will be apparent from the foregoing description that my method consists in exact tuning but mechanical overthrow, as contradistinguished from exact adjustment without any overthrow, but with over-tuning. 80 The present method may be stated in a few words as follows: A reed is cumulatively flexed to store up energy, the point of reversal or cut-off of the energy being determined at this mechanism, leaving the reed 85 or moving body to give the actual stroke and to take the corresponding recovery by means of the stored energy thus suddenly concentrated and released. It will be observed that the instantaneous stroke is of 90 great importance. The sudden stoppage of the energizing armature is of importance in order to give this instantaneous stroke, and the use of stiff and normally unresponsive parts is of importance in order to prevent the storing up of energy in beats of any 95 but the particular frequency called for. It is to be observed that I make the spring, d⁴, stiff, and by reason of the cross-connection thereon of the leaves of the armature, there 100 is a torsional, that is to say a very strong resistance to the first movements on the part of the armature. The spring, d⁴ itself may be tuned like a reed, but whether it is or not, it is so stiff that no momentary current impulses will budge the armature, this only being accomplished by the normal increments 105 of the proper periodic currents.

110 I am aware that there are many changes in detail that may be made in the invention thus described, without departing from the spirit or the principles involved; and I wish it understood quite clearly that I do not limit myself to the specific form shown for my ringer but include within the scope of 115 the claims which I shall make, all possible forms by which the invention may be practised, that is to say by which the principles upon which I rely may be incorporated and brought under control.

120 Having thus described my invention, what I claim and desire to secure by Letters Patent is:

1. In an electric bell an armature and clapper rod formed integral of punched metal, and comprising a pair of blanks each having a body portion and an extended tongue, each being bent with the tongue perpendicularly to the body portion, and the two tongues being secured together to form 125 130

- the clapper rod, while the two body portions project oppositely and in the same plane to form the armature, substantially as described.
- 5 2. In an electric bell, a **T** shaped armature and clapper rod composed of two **L** shaped members formed integral and having their stems secured together, substantially as described.
- 10 3. A vibrator for electromagnets comprising a supporting spring, and a pair of **L** shaped members each having a broad body, a drop leaf, and an extended tongue, the two tongues being secured together to form the 15 vibrator, the two drop leaves being secured together on opposite sides of the spring to form the support, and the two broad bodies extending in opposite directions and transversely to the spring to form the armature, substantially as described.
- 20 4. In a harmonic ringer, an electromagnet, a gong, an armature clapper rod and clapper rigidly associated, such armature adapted to be operated by such electromagnet to cause 25 such clapper to strike the gong, a yoke supported by such electromagnet, means for supporting and pivoting such armature consisting in a prismatic spring provided with end clamps for supporting it from such yoke, such spring adapted when such electromagnet is not energized to maintain such clapper in proper position relatively to such gong, and such end clamps adapted to permit 30 adjustment of such spring relatively to such yoke.
- 25 5. In a ringer, a pair of electromagnets, a pair of gongs, a frame for rigidly associating such electromagnets and gongs, an armature adapted to be operated by such electro- 35
- magnets, a clapper rod and clapper rigidly 40 associated with such armature, a non-magnetic yoke supported from the operating ends of such electromagnets, means for supporting and pivoting such armature consisting in a prismatic spring provided with end 45 clamps for supporting it from such yoke, such spring adapted when such electromagnets are not energized to maintain such clapper out of engagement with such gongs and such end clamps adapted to permit adjustment of such spring relatively to such yoke.
6. Means for adjusting the armature and clapper rod of an electric bell which comprise a rigid yoke secured upon the frame 55 of the bell, a transverse member secured to the armature and clapper rod and supported by such yoke, means for effecting adjustment of such transverse member laterally thereof in such yoke, and means for locking such 60 member in a desired adjustment.
7. Means for adjusting the armature and clapper rod of an electric bell which comprise a rigid yoke secured upon the frame of the bell, a transverse member secured to the 65 armature and clapper rod and supported by such yoke, means for effecting angular adjustment of such transverse member in such yoke to adjust the air gaps of the armature, and means for locking such member in 70 a desired adjustment.

In testimony whereof I affix my signature in presence of two witnesses.
